UNITED STATES PATENT OFFICE.

CHARLES W. PRESCOTT, OF ROCHESTER, NEW YORK, ASSIGNOR TO GENERAL RAILWAY SIGNAL COMPANY, OF ROCHESTER, NEW YORK.

RAILWAY-CAR-CLASSIFICATION SYSTEM.

Application filed January 14, 1926. Serial No. 81,245.

This invention relates to a system for classifying railway cars.

At the junctions of various railway systems, and particularly at the larger railway centers, where freight trains are brought in from various directions, it is found that practically all of the cars must be reswitched and reclassified into new trains radiating out in various directions. For this reason it has been found to be expedient to bring these freight trains into a classification yard or system and to re-classify the cars into new trains each of which is made up only of cars having the same destination. This classification or re-classification of cars has generally been accomplished by providing a main track or lead, which is either elevated above the yard or has a hump therein over which the train is pushed, and in allowing one or more cars to be released one at a time, so as to ride off of the hump through a suitable arrangement of switches, which lead to a large number of classification tracks. In order to retard the various cars as they are about to enter their respective classification tracks suitable car retarders or track brakes are employed this in order to reduce the speed to a value at which no harmful impact will occur if they reach cars already standing on such classification tracks. In constructing classification yards of this kind several obstacles are generally encountered; quite often it is necessary to build an artificial hump for accelerating the cars unless the natural layout of the land is such that the desired acceleration may be obtained from a natural grade; and also, if substantially all of the kinetic energy which is still stored in the cars as they reach the classification track is to be absorbed by retarders or track brakes it has been found that a large amount of frictional braking of each car is necessary. This latter conclusion, of course, being based on the assumption that the cars are accelerated to an appreciable speed in order to increase the classifying capacity of the yard. In other words, since a portion of the yard at least, namely the main track and certain of the switches, is common to all of the cars to be classified it is readily seen that the cars must move at an appreciable speed in order that the desired number of cars may be classified in a particular period of time, and

in such classification with the cars accelerated to such a speed a large amount of kinetic energy must be absorbed by the track brakes in order to reduce the speed of such cars to a safe value upon entering the classification tracks.

With the above and other important considerations in mind, it is proposed in accordance with the present invention to solve the problem of absorbing the kinetic energy stored in the cars during the time they are being classified, and the problem of grading a yard, by a single and the same solution; namely, by excavating that portion of the yard in which the classifying or switching of the cars takes place, assuming of course that there is a certain grade in the natural contour of the land, and if this is not true such a grade is preferably artificially created, thereby not only forming an accelerating hump but also leaving a decelerating or retarding hump. This excavation is preferably such that the momentum a car attains when it enters such excavated or depressed part of the yard, that is when it goes down the accelerating hump, is sufficient to carry such car through the necessary switches and again carry it up out of this excavation, conveniently called a retarding hump, and cause it to enter the classification track. In other words, it is proposed in accordance with the present invention to employ gravity not only for accelerating the cars but also employ gravity in again retarding the car after it has been diverted into the proper classification track.

Other objects, purposes and characteristic features of the invention will in part appear as the description thereof progresses, and in part be obvious from the drawing.

In describing the invention in detail reference will be made to the accompanying drawings in which:—

Fig. 1 is a plan layout view illustrating conventionally a railway classification yard laid out and graded in accordance with the present invention; and

Fig. 2 is a sectional elevation of the yard shown in Fig. 1, and more particularly illustrates the general contour of the yard.

Referring to the drawings the main lead or main track 1 has been shown at the extreme left. This main track 1 diverges into two ladder tracks numbered 2 and 3,

respectively. The ladder track 2 has a plurality of classification tracks diverging therefrom of which the tracks 4 and 5 only have been shown, and from the ladder track 5 3 diverge a plurality of classification tracks, such as the tracks 6 and 7. The particular track 2 or 3 of these ladder tracks, may be selected by operating the switch S^1 through the medium of a switch machine SM^1 controlled by the lever L^1 in the tower; whereas the classification tracks 4, 5, 6 and 7 may be selected by the switches S^3 , S^2 , S^4 and S^5 respectively, these switches being operated through the medium of switch machines SM controlled by levers L having corresponding exponents.

In each of the various classification tracks is provided a retarder or track brake, which may be of any suitable type but is preferably a track brake of the type and construction shown in the application of Winthrop K. Howe, Ser. No. 70,599 filed November 21, 1925, this retarder being one of the type in which brake shoes on opposite sides of 25 the rails engage and grip the wheel sides of a passing car and in so doing retard the same. These retarders have been designated by letters R^1 , R^2 , R^3 , R^4 and R^5 , and are controlled in a manner as disclosed in said 30 Howe application by circuit controllers C having exponents corresponding to those of the retarders which they control. Further, the main lead 1 is also provided with a retarder R controlled by the circuit controller 35 C , whereby the degree of acceleration of a car riding down the accelerating hump AH may be selected to a limited extent at least. It is desired to point out at this time that the retarding hump RH represents a vertical incline which is appreciably less than 40 the vertical distance of the accelerating hump AH , this difference between the accelerating hump and the retarding or decelerating hump being such that each and 45 every car is assured to roll beyond the retarding hump RH as it moves through the classification yard in the normal direction of traffic as indicated by the arrow.

During classifying operation a train of 50 cars in preferably pushed from left to right by a locomotive or other suitable means, and as the cars reach the accelerating hump they are released one at a time or in groups having the same destination, and if these cars 55 are extremely heavy, as may be ascertained by the operator in the tower T by looking at the train sheet he will partially restrict the acceleration of the car as it runs down the accelerating hump by applying the track 60 brake R to such a degree as is deemed necessary, so that the cars in each case have the desired speed when passing through the classification portion of the yard, which portion is confined within the space between the 65 accelerating hump AH and the retarding

hump RH . The operator may also ascertain from his train sheet what the destination of each car of a train which is being classified is. In accordance with this information he may operate the switches, such as, S^1 , S^4 and S^5 as conditions require and at the same time he will be in readiness to operate the retarder of the particular classification track into which the particular car has been switched so that this car may be ultimately retarded to the desired extent.

In certain classification systems where the weather conditions are not very changeable, and especially where it is generally warm and the temperatures do not fluctuate appreciably the retarder R on the main lead may be omitted, this retarder being particularly used to avoid undue acceleration either because the weight of the car as compared with its rolling friction is high, this ratio varying considerably with the variations of temperature due to gumming up of the lubricant ice and snow on the rails, and the like, or because the particular car in question has very few bends, switches and frogs to take and for this reason should be retarded a little more by the retarder R on the main track. Also, the retarders in the various classification tracks may not be absolutely necessary depending on local conditions, but are preferably employed in order to restrict the ultimate car speed of the various cars which are classified to substantially the same value, the amount of deceleration or retardation of the various cars naturally being somewhat different by reason of the ratio of the total weight of a particular car to that of its rolling friction. Also, by reason of the fact that certain cars traverse more curves and switches than do other cars, it is considered expedient if not essential that the track brakes in the various classification tracks be employed.

It is thus seen, that in accordance with the present invention the cars to be classified are accelerated to a suitable high speed so as to permit a large number of cars to traverse the classification portion of the classification track and be separated and diverted into the proper classification track within a limited period of time and that the energy necessary to accelerate the cars to this speed is not entirely wasted by being absorbed by track brakes, but is used in lifting the car to a higher level, thus permitting a much higher car speed to be attained with the same or even a smaller amount of energy than was used in previous systems not employing such a retarding hump, and that by reason of the conversion of the kinetic energy of the moving cars into work (lifting the cars to a higher level) requires less energy to be absorbed by frictional braking means, thus resulting in less wear of the track brakes and

a smaller amount of track braking or retarding equipment; that is, less number of rail feet of track brakes. Also, the problem of grading a yard is much simplified because the yard as a whole may be substantially level and the classification portion of the yard is a hollowed out or depressed portion of the whole classification may be obtained solely by excavating. If the natural contour of the land should be substantially level the ground removed from the depressed or excavated portion of the classification yard may be used to raise the level of the main track or lead 1 toward the left of the 15 tower T.

The storage portion of the classification yard, that is, the portion to the right of the retarding hump RH is preferably graded so as to have a down grade in the normal direction of traffic of a value to practically overcome car friction, that is, a downgrade which will under average condition be sufficient to keep the cars in motion. Although in the particular arrangement shown in the 20 drawings, all of the various remote controlled devices are controlled from one tower, it is desired to be understood that more than one tower may be used, if desired. For instance, one or more separate 25 retarder towers having levers for controlling retarders may be built at a point where the speed of the cars passing through the retarders beyond the retarding hump RH may be closely observed, or if a single tower is 30 used as shown in the drawings suitable speed indicating means may be employed for indicating to the operator in the tower what the speed of a particular car when traversing a particular track portion is. Also in the 35 particular arrangement illustrated no inclined grading to compensate at curves has been shown, such inclining of the curves in the tracks may be resorted to in accordance with standard track laying practice and if 40 desired the retarding hump of each classification track may be located to suit local conditions in which event the retarding hump will probably be in the form of an arc, also some of the classification tracks 45 may be elevated higher than others so as to compensate for difference in track resistances due to curves and switches of the various classification tracks, if desired.

Having thus shown and described only a 50 single embodiment of the present invention and having shown this embodiment rather conventionally it is desired to be understood that this has been done for the purpose of illustrating the nature of the invention 55 rather than its scope or the exact track layout arrangement or the exact grading preferably employed in practicing the invention; and the various changes and modification 60 may be made to adapt the invention to the 65 particular classification system to which it

is to be applied, without departing from the scope of the invention or the idea and means underlying the same.

What I claim as new is:—

1. The method of classifying railway cars 70 which consists in; firstly running the cars down an inclined track leading to a large number of classified tracks through switches, said inclined track having the desired slope and altitude to bring the cars to a rather 75 high speed; secondly in running the cars up a decelerating incline after they have entered the proper classification track so as to retard them and absorb a large percentage only of the kinetic energy stored therein; 80 and thirdly in retarding the cars to the ultimate desired speed on substantially level track by suitable mechanical car retarding means after they have passed beyond the decelerating incline. 85

2. The method of classifying cars of railway systems which consists in; running the cars one or more at a time down an incline; in switching them into the proper classified track when running at a high speed at the 90 bottom of said incline; and in running them up another but less pronounced incline and then onto a track beyond; whereby the cars are moved for a time at a very high speed and are then again retarded without wasting 95 the kinetic energy stored therein while running at such speed by car braking means.

3. The method of classifying cars of railway systems which consists in; running the cars one or more at a time down an incline; 100 in switching them into the proper classified track when running at a high speed at the bottom of said incline; in running them up another but lower incline; and in retarding the cars to the desired ultimate speed after 105 they have passed beyond said last mentioned incline by suitable mechanical car retarding means.

4. The method of classifying cars of railway systems which consists in; running the 110 cars down an incline; in operating suitable switches at the foot of such incline to positions so as to divert the car leading to the proper classification tracks to which such switches lead; and in running them up 115 another but less pronounced inclined and onto track beyond for the purpose of retarding the cars and prevent them from colliding with cars standing on such classification tracks, without wasting the kinetic energy 120 stored in these cars; whereby the kinetic energy of the moving cars is used in moving such cars to a higher level.

5. In a system for classifying railway cars; the combination with a railway yard 125 having a main track leading into a large number of classification tracks through suitable track switches; power operated means for operating said switches from a distant point, the contour of said yard being such 130

that a car moving towards said classified tracks from said main track is run down an accelerating incline so as to reach a rather high speed in passing through said switches, 5 and the contour is further such that the cars in entering their respective classification tracks are required to run up a retarding or decelerating incline insufficient to bring the car to a full stop; and suitable mechanical 10 car retarding means for further retarding the cars after they have passed beyond said retarding incline.

6. In a railway car classifying system, a railway yard having a main track leading to 15 a number of classification tracks through switches, an accelerating hump and a substantially level portion of track preceding the hump, in the main track, a retarding hump and a substantially level portion of 20 track following the hump, in each of the

classification tracks, with the last said level portion of track situated at a lower level than the corresponding part of the main track.

7. In a railway car classifying system, a railway yard having a main track leading to a number of classification tracks through switches, an accelerating hump and a substantially level portion of track preceding the hump, in the main track, a retarding hump and a substantially level portion of track following the hump, in each of the classification tracks, with the last said level portion of track situated at a lower level than the corresponding part of the main track, distance operated power track brakes 30 on the level portion of track of the classification tracks.

In testimony whereof I affix my signature.

CHARLES W. PRESCOTT.
